J. P. NIELSEN

BRUSH AND HOLDER ATTACHMENT FOR ERASERS.

Filed Sept. 26, 1921

Inventor:

Jens P. Nielsen

by *Albert Scheibh*
Attorney

Patented July 15, 1924.

UNITED STATES PATENT OFFICE.

JENS P. NIELSEN, OF CHICAGO, ILLINOIS.

BRUSH AND HOLDER ATTACHMENT FOR ERASERS.

Application filed September 26, 1921. Serial No. 503,223.

To all whom it may concern:

Be it known that I, JENS P. NIELSEN, citizen of the United States, residing at Chicago, Illinois, have invented certain new and useful Improvements in a Brush and Holder Attachment for Erasers; and I do hereby declare the following to be a full, clear, and exact description of the invention, such as will enable others skilled in the art to which it appertains to make and use the same.

My invention relates to pencil and ink erasers and in some of its various aspects aims to provide simple, inexpensive and unusually effective means for equipping such an eraser with a brush, for supporting the eraser when not in use, and for facilitating the effective handling of the eraser when the attached brush is to be used.

In one aspect my invention relates to a combined supporting and brush-holding attachment for erasers and aims to provide an unusually simple and strong construction for this purpose and one in which the holder portion will keep the brush freely supported when the resulting appliance is hooked upon the frame of a typewriter. Furthermore, it aims to provide a construction in which the supporting or holder portion will not be in the way when the brush is to be used, but will be conveniently disposed for facilitating the firm grasping of the appliance and the effective manipulating of the brush without requiring an undesirably tight grasping of the same by the hand of the user. With this latter purpose in mind, my invention aims to provide an eraser attachment having a holder portion adapted for supporting the complete appliance in a desirable position, and also adapted for overhanging and engaging one portion of the hand of the user while permitting other portions of the same hand to be employed effectively in grasping the appliance and in exerting the desired pressure on the brush when using the latter.

More particularly, my invention aims to provide a brush and holder attachment for erasers which will maintain the brush and the holder portions in a desirable relative disposition and which will permit the entire attachment to be rotated freely about the axis of an eraser when the latter is of the disk or so-called circular type. It also aims to provide a simple, cheaply constructed and firm mounting for the brush proper and aims to dispose the brush in a plane in which

it can effectively be employed without tiring the hand of the user. Still further and also more detailed objects will appear from the following specification and from the accompanying drawings, in which—

Fig. 1 is an elevation of a disk eraser equipped with my invention, with dotted lines showing a desirable position of the hand of the user when the brush is being employed.

Fig. 2 is a rear elevation of the same embodiment showing the same as it appears when supported on a side of the frame of a standard typewriter.

Fig. 3 is a plan view of the parts shown in Fig. 2.

Fig. 4 is an enlarged and fragmentary section taken along the correspondingly numbered line in Fig. 3 and showing the method of securing the brush-holding socket to the adjacent arm of the attachment.

Fig. 5 is an enlarged and fragmentary perspective view showing the arm adjacent to the brush before the socket for the latter is attached.

Fig. 6 is a corresponding bottom view of the brush-holding socket before the latter is attached to the arm of Fig. 5.

Fig. 7 is an elevation of another embodiment, namely one in which the brush extends substantially tangential of the eraser.

In accomplishing the purposes of my invention after the manner of the accompanying drawings, I substitute a special form of metal attachment for one of the disks or spool ends as commonly employed at opposite sides of an ordinary disk eraser. This special attachment consists of a metal plate 1 having a pair of arms diverging from each other at an acute angle, the metal plate for this purpose being desirably secured to the eraser 2 by a hollow shaft or rivet 3 extending through a corresponding axial bore in the disk and clinched over a plain flat washer 4 disposed at the opposite side of the disk.

One of the arms 5 of the forked metal plate as thus attached to the eraser is desirably recurved upon itself so as to present its tip 6 towards the axis of the eraser and so as to afford a hook for supporting the complete appliance after the general manner of the U. S. Patent #1,247,714, issued November 27th, 1917 to Walter B. Pershing. The other arm 8 is equipped for supporting a brush and for this purpose desirably has

its outer end 9 bent substantially at right angles to the general plane of the arm and preferably in a direction in which this bent end overhangs the edge of the eraser disk, 5 thereby affording a suitable bottoming support for a ferrule or socket 10 carrying the brush proper. This brush-holding socket desirably is flattened to correspond substantially to the flattening of the eraser disk 10 and desirably has an integral bottom 11 equipped with a pair of perforations to permit the entry of corresponding fingers 12 formed from the bent overhanging end 9 of the said arm 8 as shown in Fig. 5. In assembling the parts, these fingers are bent over against the bottom of the socket so as to clamp this bottom against the arm end 9 as shown in Fig. 4, thereby firmly securing these parts to each other. Then the bristles 20 13 of the brush are slipped into the socket and secured in position by cementing or the like after the usual manner.

With the appliance thus constructed, it will be obvious from Figs. 2 and 3 of the drawings that the entire appliance can readily be supported clear of the desk or table of the user by simply snapping the hook 5 over the frame portion 15 of an ordinary typewriter, thus preventing both 30 the eraser and the brush from picking up the dust which easily accumulates on the relatively large surface of the table or desk. It will also be evident by mounting the brush so that it will slope upwardly when the appliance is thus supported, the brush portion will not be in the way of the user of the typewriter.

When the appliance is to be used as an eraser this can readily be done in the usual manner as the hook 5 can easily be of sufficient size for clearing the thumb of the user's hand when the appliance is being grasped for erasing purposes. So also, 40 the pivotal mounting of my attachment on a disk eraser permits the eraser proper to be rotated when desired for bringing fresh portions of the same into operative positions.

When the brush portion of the appliance 50 is to be used, the appliance is desirably held as shown in Fig. 1, or with the tip of the user's thumb under the hook so that the hook overhangs this thumb tip and affords a stop for the thumb. Owing 55 to the angular diversion of the hook from the arm carrying the brush, such a position of the hand readily brings the fore finger of the same hand opposite the eraser directly back of the hook and brings the middle finger of the hand in substantial alignment with the brush-holding arm. The appliance can, therefore, be grasped with the thumb and said two fingers and with 60 the middle finger pressing flatwise against one side of the socket holding the brush,

so that the desirable pressure can readily be exerted on the brush by the middle finger. In other words, the hook on the appliance helps to hold the same in engagement with the thumb while disposing it 70 so that the middle finger will readily have an effective leverage for using the brush. By bending the free end of the attached arm as above described so as to bring the further side of the brush-holding socket 75 substantially into the same plane with the further described eraser, I make it easy for the user's hand to reach the said socket in this manner, while also improving the appearance of the appliance as a whole. 80 However, while I have illustrated and described my brush-holding attachment as employed on an eraser of the disk type and as pivotally mounted on the eraser, I do not wish to be limited to this arrangement of the 85 same, nor to the joint use of the holding hook in connection with the brush-supporting portion of my attachment. Neither do I wish to be limited to other particulars of the construction and arrangement herein disclosed, it being obvious that the same might be modified in many ways without departing from the spirit of my invention or from the appended claims. For example, Fig. 7 shows another embodiment in which the brush-holding socket is integral with the supporting arm and in which the brush 90 is substantially tangential of the eraser disk instead of extending radially of the disk, as in the other figures. 100

I claim as my invention:—

1. An eraser and brush combination, comprising a disk eraser, a pair of arms extending substantially radially of the eraser and at an acute angle to each other, 105 one of the arms being equipped with a hook adapted to serve as a supporting hook for the said combination and also disposed for overhanging the thumb tip of a hand grasping the eraser, a brush socket carried by 110 the other arm and disposed for engagement by a finger-tip of the same hand, and a brush mounted in the socket.

2. An eraser and brush combination, comprising a disk eraser, and a combined 115 supporting and brush attachment pivoted to the eraser coaxially with the eraser; the said attachment comprising an arm terminating in a hook adapted to support the said combination and also adapted to overhang the thumb tip of a hand grasping the eraser, and a second arm member including a brush, a portion of the second arm member being disposed for engagement by 120 a finger-tip of the same hand.

3. The combination with a disk eraser, of a carrier spool on which the eraser is rotatably mounted, one head of the spool having a pair of arms extending radially 125 of the spool at an acute angle to each other, 130

one of the arms having its free end re-curved and the other arm having its free end bent at right angles to the main portion of the arm, a ferrule secured to the last named bent arm portion, and a brush socketed in the ferrule.

4. An erasing appliance as per claim 3, in which the ferrule has a bottom engaging the said bent arm portion and equipped

with perforations, and in which the said bent arm portion has fingers projecting through the said perforations and bent against the ferrule bottom to clamp the ferrule to the said bent arm portion.

Signed at Chicago, Illinois, September 15
17th, 1921.

JENS P. NIELSEN.
